WIRE TIGHTENER

Frank J. Jellinek, R.R. 1, Bismark, Mo. 63624

Filed Feb. 2, 1973, Ser. No. 329,032

Term of patent 14 years

Int. Cl. D8—05

U.S. Cl. D8—44

FIG.1

FIG.2

FIG.3

FIG.4

FIG.5

FIG.6

FIG. 1 is a perspective view showing a wire tightener embodying my new, original and ornamental design, with a fragment of a wire shown in broken lines for illustrative purposes only;

FIG. 2 is a top plan view of the same wire tightener showing the wire tightener in folded position;

FIG. 3 is a side elevational view of the same wire tightener as in FIG. 2;

FIG. 4 is a left end elevational view of the same wire tightener as seen in FIG. 3;

FIG. 5 is a right end elevational view of the same wire tightener as in FIG. 3; and,

FIG. 6 is a sectional view of the same wire tightener taken along the line 6—6 in FIG. 2.

I claim:

The ornamental design for a wire tightener, as shown and described.
